UNITED STATES PATENT OFFICE

HARRISON D. FLEGEL, OF RACINE, WISCONSIN, ASSIGNOR, BY MESNE ASSIGNMENTS, TO HAMILTON BEACH MANUFACTURING COMPANY, OF RACINE, WISCONSIN, A CORPORATION OF WISCONSIN

DRINK MIXER

Application filed August 27, 1926. Serial No. 131,828.

My invention relates to improvements in drink mixers, more particularly to the motor driven type of mixers, and to flexible supporting means for the motors of such mixers; 5 but my invention is a general application to the support of devices in which a certain amount of vibration is inherent, as motors of all types, and I do not wish to be limited to its use in drink mixers. In drink mixers having a permanently attached agitator 10 shaft of the usual length, it is practically impossible to have this length of shaft run true and without vibration, and when the motor is rigidly mounted there is excessive 15 wear on the bearings, the machines are more or less noisy in operation, and are generally unsatisfactory.

One object of my invention is the provision of a flexible motor support for the 20 driving motor of drink mixers of this type having an agitator shaft permanently attached to the motor shaft, thereby eliminating excessive wear on the bearings, the noise incident to such a motor when rigidly 25 supported and other disadvantages of the latter construction.

Another object of my invention is the improvement of this type of mixer by adapting the same to be mounted on a more or less 30 rigid one piece cast metal support by means of a resilient motor mounting.

Another object of my invention is the provision of a flexible and resilient motor mounting permitting a limited amount of motor 35 vibration in any direction.

Other objects and advantages of my invention will more fully appear from the accompanying description and drawings, in which several embodiments of the invention 40 are shown by way of illustration, and in which similar characters of reference apply to similar parts.

The invention consists in the combination of means hereinafter illustrated and particularly pointed out in the claims.

In the drawings Figure 1 is a vertical figure of the preferred form of my invention, showing a complete mixer.

Figure 2 is a vertical axial section of the motor mounting shown in Figure 1. 50

Figure 3 is a view in perspective of the disassembled parts of the mounting shown in Figures 1 and 2.

Figure 4 is a similar view of a modification illustrating the use of helical springs and 55 a plurality of fastening screws.

Figure 5 is a vertical elevation, partially broken away, showing a modification of my invention embodied in the straight tubular support. 60

Figure 6 is a vertical elevation partially broken away, showing another modification, and

Figure 7 is a detailed view of another type of spring which may be used in my invention. 65

Referring to Figures 1 to 4, 10 represents a rigid one-piece support, preferably formed of cast metal comprising a hollow base 11, resilient feet 12, and a hollow goose neck standard 13. The mixer motor 14 with its 70 stirrer shaft 15 is carried by the support 10 through the medium of a supporting member 30 including supporting flanges 16 and screws 17. The supporting member 30 also comprises a casing for my improved resilient 75 mounting.

The goose neck 13 is formed with a seating surface 18, preferably a plane surface provided with a threaded bore 19, communicating with a hollow goose neck 13 and the hollow standard 10 for reception of conductors transmitting energy to the said motor. The seating surface 18 is provided with a lateral annular flange 20, forming a cylindrical chamber 21 open at one end and having the bore 19 at the other end. The seating surface 18 is also provided with a fixed projecting pin 23 extending at right angles to the said surface for a purpose hereinafter to be described. The friction plate 22 consists of a 80 85 90 95

relatively thin disc of steel, adapted to be received in the chamber 21, covering the seating surface 18 and having a hole 24 aligned with the bore 19. The plate 22 is provided with a notch 25, comprising abutments in opposed relation adapted to cooperate with the pin 23 to hold the said plate from rotation. The resilient member 26 consists of a tempered spring plate having a central perforation 27 and a periphery laterally slit and crimped or stamped to form a spring plate having a plurality of tongues 28 forwardly bent in pairs, and equally spaced in circular arrangement. The spring 26 is likewise provided with a hole or slot 29 adapted to receive the pin 23 projecting through the said spring. The cover member 30 comprises a flat circular portion 31 of size sufficient to cover the flange 20 and is provided with a rearwardly extending annular flange 32, forming a cover member for the chamber 21, of a slightly loose fit for a purpose further to be described. The cover 30 is also provided with the forward motor supporting flanges 16, shaped to conform to the contour of the motor casing and adapted to support the latter by screws or other fastening means through the holes 60. The cover member is also provided with the central bore 33 adapted to be substantially aligned with the holes 24, 27 and bore 19 when in assembled relation, and the said cover member is also provided with the perforation 34 slightly oblong in shape or larger than the pin 23, adapted to receive the pin 23 when in assembled relation, but permitting a slight amount of rotary movement about the axis of the bore 19. The cover member 30 and the seat 18 are held in assembled relation with the friction plate 22 and the resilient member 26 inside the chamber 21 by the hollow screw bolt 35, provided with screw threads 36 to be threaded in the bore 19, and with the head 37 and the slot 8 for facilitating its removal. In order to permit a slight amount of movement in all directions between the supporting cover 30 and the rigid seating surface 18 with its screw bolt 35, the bore 33 need only be made slightly larger than the bolt 35, but I prefer also to form the bearing portion of the head 38 with the curved cross section 38a and likewise to provide a curved annular seat 39 on the said head in the cover 30, as well as allowing play between the bolt 35 and the bore 33, thus providing a limited universal joint between said cover and bolt.

In assembling the structure shown in Figure 3, the plate 22 is first placed in the chamber 21, with the slot 25 receiving the pin 23; the spring 26 is superimposed on the plate 22 in the same manner, and the cover 30 placed over both plate and spring with the pin 23 in the aperture 34 and the flange 32 loosely surrounding the flange 20. The screw bolt 35 is then inserted through the bores 33, 27 and 24, and is threaded into the bore 19 to such

position as will tension the spring tongues 28 toward the plane of the flat portions of the spring 26, but will still permit a further tensioning, maintaining the inside cover surface 40 in a slightly spaced relation to the flange 20. The spring plate will then hold the cover 30 firmly against the shoulder 38a of the bolt 35, but due to the limited universal joint and play provided between the bolt 35 and bore 33, and between the cover 30 and the flange 20, the supporting plate 30 may be moved slightly in any direction relative to its support and is flexibly and resiliently mounted. The elongation or play of the hole 34 about the pin 33 also permits a slight rotary or swivel motion which allows motor vibration in all directions. By means of the foregoing combination, I provide a flexible and resilient motor support which absorbs and dampens the vibrations incident to the motor, thereby greatly reducing the wear on the bearings and the noise of operation, particularly in the case of motors having a long stirrer shaft. The supply conductors are brought through the opening provided by the hollow bolt 35, providing a concealed and protected system of wiring which is also of great advantage.

In the modification illustrated in Figure 4 I have shown my invention adapted to be used with helical springs, instead of the spring plate 26, and my invention is susceptible of many different embodiments including any form of spring, as the flat spring shown in Figure 7, helical springs, flexible metal gaskets, rubber gaskets, or any resilient means between the motor and column. In this embodiment, the friction plate 22 may also be used but is not required, as the springs 41 may be seated in the cylindrical bores 42 in the seating surface 18, the forward end of the springs 41 bearing directly on the rear face of the cover 30 which may also be provided with similar sockets. The assembly may be held in resilient spaced relation by a plurality of screw bolts screwed in bores 43 and extending through the holes 44 but in such case the holes 44 should be made slightly larger than the said bolts to permit the requisite amount of play. The assembly and cooperation of the parts of this embodiment is similar to that previously described.

In Figure 5 I have shown another modification of my invention as applied to the tubular standard member. The tubular standard member 45 is provided at its upper end with a flat supporting plate 46 extending substantially at right angles to the said standard. The said plate is adapted to be received in the cover member 47, also provided with a motor supporting flange 49 and the plate 47 comprises the top cover plate 54 and a depending flange 55. The said cover may be surrounded by the ball grip 50 for use in manual manipulation of the standard in sliding the

cover and standard, and means for preventing rotation of said friction plate.

7. In a drink mixer of the class described, the combination of a supporting standard having a cup shaped recess formed therein, with a cover for said cup having flanges for attachment of a motor casing, a friction plate in the bottom of said cup, spring means in said cup engaging said cover at a plurality of points, a universal joint connecting said cover and standard, and means for preventing rotation of said friction plate, and limiting rotative movement of said cover on said cup.

8. In a drink mixer of the class described, the combination of a supporting standard having a cup shaped recess formed therein, with a cover for said cup having flanges for attachment of a motor casing, and a universal joint connecting said cover and standard, said joint and standard being hollow to provide a continuous conduit for electrical conductors.

9. In a drink mixer of the class described, the combination of a hollow supporting standard having a cup shaped recess forming a seating surface and a threaded aperture centrally located therein, a cover for said cup having an enclosing flange about said cup and an aperture aligned with said first mentioned aperture, resilient means between said cup and cover and a hollow screw bolt in said threaded aperture having a limited universal movement with said cover.

10. In a drink mixer of the class described, the combination of a hollow supporting standard having a cup shaped seating surface and a threaded aperture centrally located therein, a cover for said cup having an enclosing flange about said cup and an enlarged aperture aligned with said first mentioned aperture, resilient means between said cup and cover, and a hollow threaded member passing through said enlarged aperture and threaded in said first mentioned aperture, said member having a head with a spherical surface beneath the same, and said cover having a complementary surface to co-operate therewith to form a limited universal joint.

11. In a drink mixer of the class described, the combination of a hollow supporting standard having a cup shaped seating surface and a threaded aperture centrally located therein, a cover for said cup having an enclosing flange about said cup and an enlarged aperture aligned with said first mentioned aperture, spring means in said cup having a plurality of points of engagement between said cup and cover and holding said cover out of contact with said cup, and a hollow threaded member passing through said enlarged aperture and threaded in said first mentioned aperture, said member having a head with a spherical surface beneath the same, and said cover having a complementary

surface to co-operate therewith to form a limited universal joint.

12. In a drink mixer of the class described, the combination of a hollow supporting standard having a cup shaped seating surface and a threaded aperture centrally located therein, a cover for said cup having an enclosing flange about said cup and an enlarged aperture aligned with said first mentioned aperture, spring means in said cup having a plurality of points of engagement between said cup and cover and holding said cover out of contact with said cup, a hollow threaded member passing through said enlarged aperture and threaded in said first mentioned aperture, said member having a head with a spherical surface beneath the same and said cover having a complementary surface to co-operate therewith to form a limited universal joint, and a pin in said cup passing through an enlarged aperture in said cover to limit its rotative movement.

13. In a drink mixer of the class described, the combination of a hollow supporting standard having a cup shaped seating surface and a threaded aperture centrally located therein, a cover for said cup having an enclosing flange about said cup and an enlarged aperture aligned with said first mentioned aperture, spring means in said cup having a plurality of points of engagement between said cup and cover and holding said cover out of contact with said cup, a hollow threaded member passing through said enlarged aperture and threaded in said first mentioned aperture, said member having a head with a spherical surface beneath the same and said cover having a complementary surface to co-operate therewith to form a limited universal joint, a pin in said cup passing through an enlarged aperture in said cover to limit its rotative movement, curved attaching flanges on said cover and a motor casing supported on said flanges.

14. In a drink mixer, the combination of a rigid support, an electric motor comprising a casing, an agitator-shaft depending from and driven by the motor, a bracket removably secured to the motor casing, and means for connecting the motor to the support comprising a resilient diaphragm confined between the support and the bracket.

15. In a drink mixer, the combination of a rigid support, an electric motor comprising a casing, an agitator-shaft depending from and driven by the motor, a bracket removably secured to the motor casing, and means for connecting the motor to the support comprising a resilient diaphragm removably secured between the support and the bracket.

16. In a drink mixer, the combination of a rigid support, an electric motor comprising a casing, an agitator-shaft depending from and driven by the motor, a bracket removably secured to the motor casing, and means

same upward and downward. The plate 46 and the cover 47 as viewed from above may be of any conformation not permitting relative rotation between the said parts when in assembled relation, except such limited motion as is provided by the play between these elements. A spring 51 of any conformation adapted to hold the cover plate 54 and the plate 46 in parallel spaced relation is interposed between said cover and plate and the hole is held in assembled relation by the screw 54, threaded in the plate 46 and passing through the enlarged hole 52 in the cover plate 54.

15 In the modification shown in Figure 6 I have shown a tubular standard with a T-shaped union for adapting said standard to the same flexible mounting used in Figures 1 to 4. The tubular standard 56 supports the special T union 57 by screw threads or other convenient fastening means and the upper end of the T union 57 is closed by the ball grip 50. The stem of the T union 57, the right side in Figure 6, is provided with a flat circular seating surface 18, which is centrally bored and threaded as at 19, for the reception of the hollow screw bolt 35 of a similar structure of the bolt already described. The pin 23 is seated in a surface 18 and the spring 26 and supporting cover 58 cooperate with these parts as in the previous embodiments, except that the friction plate may be omitted where the surface 18 is machined or where 25 for other reasons a friction plate is unnecessary, and it will be noted that as the seating surface here is the end of a flat cylinder, the casing member for the spring is provided by a longer flange 32 on the supporting cover. In this modification, as in others, it is 30 essential that a limited amount of play be permitted between the cover 58 and the bolt 35 as well as between the cover 58 and the exterior walls 59 of the seating surface 18, and 35 the supporting cover is resiliently held in spaced relation to the seating surface 18 by the tension of the spring 36 against the bolt 35. The bolt 35 and cover 58 may be likewise provided with a limited universal joint, and 40 each of the modifications illustrated may be 45 adapted interchangeably for use with either coil or flat springs by providing the bores 42 for helical springs.

It should be also noted that any number of 55 springs may be used down to a single large helical spring disposed about the central bolt 53, provided the spring or springs are so arranged as to resiliently support the cover 30 against vibration in all directions and 60 provided sufficient points of contact are present between the said springs, the seating surface and the cover to resiliently hold the cover in parallel spaced relation to the seating surface.

65 The invention is not to be understood as re-

stricted to the details set forth, since these may be modified within the scope of the appended claims without departing from the spirit and scope of the invention.

Having thus described my invention, what 70 I claim as new and desire to secure by Letters Patent of the United States, is:

1. In a drink mixer of the class described, a rigid supporting standard having a seating surface, a friction plate on said surface, a resilient member on said friction plate, a loose casing member for surrounding said seating surface and enclosing said plate and spring, and an adjustable stop member resiliently holding said casing in spaced relation to said 80 seating surface.

2. In a drink mixer of the class described, a rigid supporting standard having a seating surface, a friction plate on said surface, a resilient member on said friction plate, a loose casing member for surrounding said seating surface and enclosing said plate and spring, and a stop member through said casing, plate and spring, providing a ball and socket connection between said casing and standard, and holding the same in spaced relation.

3. In a drink mixer of the class described, a rigid supporting standard having a seating surface, a friction plate on said surface, a resilient member on said friction plate, a loose casing member for surrounding said seating surface and enclosing said plate and spring, a stop member through said casing, plate and spring, providing a ball and socket connection between said casing and standard and holding the same in spaced relation, and a pin on said standard extending through said friction plate, spring and casing, permitting slight rotation of said casing on said stop.

4. In a drink mixer of the class described, the combination of a supporting standard having a cup shaped recess formed therein, a cover for said cup having flanges for attachment of a motor casing, a universal joint 110 connecting said cover and standard, and spring means in said cup engaging said cover at a plurality of points.

5. In a drink mixer of the class described, the combination of a supporting standard 115 having a cup shaped recess formed therein, with a cover for said cup having flanges for attachment of a motor casing, a friction plate in the bottom of said cup, spring means in said cup engaging said cover at a plurality 120 of points, and a universal joint connecting said cover and standard.

6. In a drink mixer of the class described, the combination of a supporting standard having a cup shaped recess formed therein, 125 with a cover for said cup having flanges for attachment of a motor casing, a friction plate in the bottom of said cup, spring means in said cup engaging said cover at a plurality of points, a universal joint connecting said 130

for connecting the motor to the support, comprising a resilient diaphragm enclosed between the support and the bracket.

17. In a drink mixer, the combination of a rigid supporting standard, having a forwardly extending upper end, an electric motor having a casing, an agitator shaft depending from and driven by the motor, a bracket to which the back of the motor casing is removably secured, and resilient means for connecting the back of the bracket to the upper end of the standard.

In witness whereof, I hereunto subscribe my name this 24th day of August, 1926.

HARRISON D. FLEGEL.
